CLAIM

The ornamental design for a reconfigurable automobile wheel, as shown and described.

DESCRIPTION

FIG. 1 is a perspective view of a reconfigurable automobile wheel with a wheel cover attached thereto in a first condition, of the new design;

FIG. 2 is a side elevation view thereof in the first condition;

FIG. 3 is a top plan view thereof in the first condition;

FIG. 4 is a rear elevation view thereof in the first condition;

FIG. 5 is a bottom plan view thereof in the first condition;

FIG. 6 is a front elevation view thereof in the first condition;

FIG. 7 is a back elevation view thereof in the first condition;

FIG. 8 is a perspective view of the reconfigurable automobile wheel without the wheel cover in a second condition;

FIG. 9 is a side elevation view thereof in the second condition;

FIG. 10 is a top plan view thereof in the second condition;

FIG. 11 is a rear elevation view thereof in the second condition;

FIG. 12 is a bottom plan view thereof in the second condition;

FIG. 13 is a front elevation view thereof in the second condition; and,

FIG. 14 is a back elevation view thereof in the second condition.

The broken lines depict portions of the reconfigurable automobile wheel that form no part of the claimed design.

1 Claim, 10 Drawing Sheets
